TWO-TEMPERATURE THERMOSTAT

Fred W. Powers, Chicago, Ill., assignor to The Powers Regulator Company, Chicago, Ill.

Application September 4, 1934, Serial No. 742,523

9 Claims. (Cl. 236—47)

My invention relates to thermostats, and particularly to a thermostat of the type known as a two-temperature thermostat; that is, an instrument adapted to control temperature in two rather widely different ranges.

It has been found to be desirable for the heat regulation of offices, school rooms, etc., from a remote point, to provide for normal thermostatic control of the heat according to the setting of the thermostats in the individual spaces, and, by the use of collateral devices, manually operable at a central point, to effect adjustment of the individual thermostats so as to provide for regulation at a much lower temperature. Thus, for operation during working hours, the individual thermostats may be set to maintain a temperature of 70°, and the control device, operable from the central point, may be arranged to change the adjustment of all thermostats to provide for the maintenance of a temperature during non-working hours of 50°. This result has been accomplished in several different manners, and in general, the operation of such devices has been satisfactory.

In all apparatus of character described, means should be provided, associated with the individual thermostats, for segregating the individual thermostats from the common low-temperature controlling means, in order that the occupant of any space may, by a simple adjustment, prevent the action that would result in a lowering of the temperature. This likewise, is common to many of the instruments now in use. However, in the device herein disclosed I provide not only for the desired functions, but in addition, I provide for a return to normal operating conditions of the instrument following a reversal of the temperature reducing action, without any necessary attention from the occupant. In other words, all that the occupant needs to do is to set the instrument for normal operation; then at the next actuation from the central point the instrument will be restored to its normal operating condition.

The invention will be more readily understood by reference to the accompanying drawing, in which;

Fig. 1 is a longitudinal, vertical, sectional view through an instrument constructed in accordance with my invention;

Fig. 2 is a sectional view on the line 2—2 of Fig. 1; and

Fig. 3 is a face view of the instrument with the cover removed.

In the drawing I have illustrated the instru-

ment as including a base plate 10 to which the various parts are secured. The instrument is enclosed by a cover 11, having a bulb thermometer 12 thereon, and openings through which adjusting keys may be inserted.

The main part of the instrument consists of a casting 13, having air passages 14—15 therein that communicate with air pipes 16—17 respectively, the pipe 16 being connected to a source of air under pressure, and the pipe 17 being connected to an air-operated heat control valve. The pipe 18, which is connected to the passage 19, is independently connected to a source of fluid under pressure, a hand valve therein (not shown) being actuated to admit air into the passage 19 for operating the adjustment-changing mechanism that constitutes one of the novel features of the instrument.

Mounted over the recess 20 in the casting 13 is a diaphragm 21, and a double valve 22—23 controls the escape of air from the passage 14 to the passage 15. A spring 24 tends to unseat the valve 22, while a spring 25 tends to seat the valve 23. A flat spring 26 overlies the valve body that is connected to the diaphragm 21, and directly overlying the spring 26 and the end of the valve body is a bridge member 27 that supports a pair of bellows 28—29. Each of the bellows contains a volatile substance selected to function within the desired temperature range. Two bellows for operation in unison are used rather than one bellows of large size. I have found that accurate operation is secured with the arrangement shown, and considerable space is saved, as a result of such use. The outer faces of the bellows are supported against an arm 30 secured at its upper end to the face of the main casting, and at its lower end having screw thread engagement with a threaded pin 31. The pin carries a small gear 32 that meshes with an indicating dial 33, a key being used to engage the squared outer end of the pin in order to rotate the same for adjustment purposes.

Mounted over a recess in the arm 30 is a small diaphragm 34, thereby providing a chamber 35 to which air is admitted through the passage 36. A stem 37 projects inwardly from the face of the diaphragm 34, through an opening, and into contact with the bridge member 38 on the outer face of the bellows, and it will be seen that as air under pressure is admitted into the chamber 35, a thrust will be exerted against the bellows that will serve, in effect, to change the adjustment of the arm 30, by separating the bridge 38 and the arm 30.

Air is admitted to the chamber 35 through the passage 36, the passage 19, and the air pipe 18 around the restriction screw 39a. This air is controlled by a valve 39 operated to closed and 5 exhaust positions by means of the threaded member 40. A spring 41 thereon tends to rotate the threaded member to a position in which the valve 39 will close the exhaust passage and admit air to the passage 36, through the branch 42. 10 When, however, the threaded member 40 is rotated by means of a key engaging the outer end thereof, air will be exhausted and prevented from entering the passage 42.

A second branch passage 43, open to the pipe 15 18, is connected to a small bellows 44 mounted on the arm 30, and adapted to expand outwardly and operate an arm 45. This arm underlies a section of a disk 46 fixed to the threaded member 40, a recess and projection 47 on the arm and 20 disk constituting means for temporary engagement in order to hold the threaded member in open position whenever the bellows 44 is distended. Preferably the disk will be given a distinctive color, and will be visible through an 25 opening in the cover.

The operation is as follows:

Assume a supply of air under pressure in the supply pipe 16 and a setting of the instrument by means of the pin 31 for a desired temperature, 30 an increase over that temperature will result in a thermal expansion of the bellows 28-29. This will cause an inward movement of the diaphragm 21, the overcoming of the spring 24, and the seating of the valve 22. Further inward 35 movement will result in unseating the valve 23, and the admission of air through the passage 14 into the space 20, and to the passage 15 leading to the air controlled heat valve, thus closing it. Upon a reversal of movement of the bellows 40 due to a cooling of the space, a reverse action will take place; that is, the valve 23 will first be closed, and then as the movement continues, the valve 22 will be opened, permitting air to exhaust and the heat valve to open. 45 When, at the close of the day, the engineer wishes to reduce the temperature of all the spaces to which heat is supplied, he opens a valve and admits air to the pipe 18. The air so admitted enters the branch 43 and distends the bellows 44 50 and swings outward the arm 45 into contact with the disk 46. Air also enters the branch 42 and the passage 36 into the space 35 causing the diaphragm 34 to be moved and to exert pressure through the stem 37, against the wall 38 that 55 overlies the bellows 28-29. This results in the equivalent of an expansion of the said bellows, and an interruption of the supply of heat. Consequently, while the pressure is exerted as described, a much lower temperature will prevail in 60 the space under regulation.

In the event that an occupant wishes to use a particular space and to have heat therein, he applies a key to the threaded member 40, turns it and the disk 46 against the tension of the spring 65 41, thus opening the valve 39 and permitting air to exhaust from the space 35 more rapidly than it can enter through the restriction screw 39a. This does not, however, stop the supply to the branch 43, and to bellows 44 which is unaffected 70 by the movement of the valve 39. Consequently, the threaded member is retained in its position due to the engagement of the recess and projection 47 on the disk and the arm 45 and normal operation of the bellows 28-29 is restored. In 75 the morning, when the engineer wishes to re-

store normal heat conditions, the supply of air in the pipe 18 is discontinued, the bellows 44 will resume its normal position and the threaded member will be returned under the influence of the spring 41, thus resetting the parts without any action by the occupant. 10

It is obvious that many of the elements shown and described may be modified and I do not wish to be limited except as indicated in the appended claims.

I claim:

1. In a device of the class described, the combination of valve means for controlling the passage of air to a heat regulating valve, a thermosensitive element for actuating said valve means, means operable by air under pressure from an independent supply for changing the valve operating function of said thermosensitive element, manually operable means for interrupting the supply of air to said means for changing the function of said thermosensitive element, and means operable by said independent supply of air for retaining said manually operable means in interrupting position only during the period when air is being supplied from independent source. 20

2. In a device of the class described, the combination of valve means for controlling the passage of air to a heat regulating valve, thermosensitive element for actuating said valve means, means operable by air from a source independent of the air controlled by said thermosensitive element for readjusting the setting of the said thermosensitive element, means operable at a remote point for controlling the supply of air through said independent source, manually operable means within the space under heat regulation for interrupting the supply of air to the device to be controlled, and means operable by said independent supply of air for retaining said manually operable means in interrupting position only during the period when air is being supplied from said independent source. 30

3. In a thermostat of the leak type, the combination of means providing a movable wall adapted, when under pressure, to affect a change of adjustment of the thermostat, an independent conduit for supplying fluid under pressure to said movable wall, a manually operable valve on said thermostat adapted to be positioned to prevent actuation of said wall by the fluid under pressure, a second movable wall carrying a detent, and means on said valve adapted to be engaged by said detent to hold the same at adjusted position so long as fluid under pressure is being supplied to said last named movable wall. 45

4. In a thermostatic instrument, the combination of a base containing air passages, a valve in said base for controlling the delivery of air to a heat valve through said passages, a thermally expansible element mounted above said base and adapted to control the said air valve, an arm connected at its two ends to said base, one end being adjustable, said arm acting as a backing for the thermally expansible element, said arm and base having an air passage connected to an independent supply of air under pressure, a fluid expansible member carried by the arm open to said last named air passage and adapted to act on said thermally expansible element to change its action on the air valve, and manually operable means also carried by said arm adapted to prevent the operation of said adjustment changing means. 60

5. In a two-temperature range thermostat, the 70

- combination of a base containing an air passage, a valve in said passage for controlling the delivery of air to a heat valve through said passage, a thermostatic element mounted above said base and adapted to control the said air valve, an arm connected at its two ends to said base, one end providing an adjustable connection, said arm acting as an outer support for the thermostatic element, said arm and base having an air passage connected to a supply of air independent of said first mentioned air supply, a fluid expansible member carried by the arm and open to said last named air passage and adapted to act on said thermostatic element to change its adjustment, and manually operable means, also carried by said arm, and adapted to interrupt the supply of air to said fluid expansible member. 5
6. In a two-temperature range thermostat, the combination of a base containing an air passage, a valve in said passage for controlling the delivery of air to a heat valve through said passage, a thermostatic element mounted above said base and adapted to control the said air valve, an arm connected at its two ends to said base, one end providing an adjustable connection, said arm acting as an outer support for the thermostatic element, said arm and base having an air passage connected to a supply of air independent of said first mentioned air supply, a fluid expansible member carried by the arm and open to said last named air passage and adapted to act on said thermostatic element to change its adjustment, and manually operable means, also carried by said arm, and adapted to interrupt the supply of air to said fluid expansible member. 10
- 15
7. In combination, a base having an air passage from a source of supply to a heat valve, a valve for controlling said passage, a thermostat for actuating said valve, a support for said thermostat mounted on, and adjustable relative to said base, a diaphragm carried by said member and adapted to exert a pressure tending to change the adjustment of said thermostat, said member having a passage for air from an independent source to said diaphragm, manually operable means on said member for interrupting the supply of air to said diaphragm, and means independent of said diaphragm and operated by the same supply of air for retaining said manual means in interrupting position. 15
- 20
8. In combination, a base having an air passage from a source of supply to a heat valve, a valve for controlling said passage, a thermostat for actuating said valve, a support for said thermostat mounted on, and adjustable relative to said base, a diaphragm carried by said member and adapted to exert a pressure tending to change the adjustment of said thermostat, said member having a passage for air from an independent source to said diaphragm, manually operable means on said member for interrupting the supply of air to said diaphragm, and means independent of said diaphragm and operated by the same supply of air for retaining said manual means in interrupting position. 25
- 25
9. In combination, a base having an air passage from a source of supply to a heat valve, a valve for controlling said passage, a thermostat for actuating said valve, a support for said thermostat mounted on, and adjustable relative to said base, a diaphragm carried by said member and adapted to exert a pressure tending to change the adjustment of said thermostat, said member having a passage for air from an independent source to said diaphragm, manually operable means on said member for interrupting the supply of air to said diaphragm, and a fluid expansible member independent of said diaphragm, and mounted on said member and connected to said last named supply of air for retaining said manual means in interrupting position. 30
- 35
- 40
7. In combination, a base having air passages, a valve for controlling said passages, a thermostatic element for actuating said valve, a fluid expansible element adapted to act on said thermostatic element to change the adjustment thereof, said fluid expansible member being adapted for operation by an independent supply of air, manually operable means for nullifying a change of adjustment of said thermostatic element, and a second fluid expansible member connected to last named supply of air, for retaining said manual means in nullifying position only during the continuance of said supply of air. 10
